DESK BASE FOR A WRITING IMPLEMENT OR SIMILAR ARTICLE

William E. L. Bunn, Fort Madison, Iowa, assignor to W. A. Sheaffer Pen Company, Fort Madison, Iowa, a corporation of Delaware

Application November 6, 1959, Serial No. 58,232

Term of patent 14 years

(Cl. D74—1)

Figure 1 is a side perspective view of a desk base for a writing implement or similar article, showing my new design;

The broken line illustration in Figure 1 of the pen and holder therefor is for illustrative purposes only.

I claim:

The ornamental design for a desk base for a writing implement or similar article, substantially as shown and described.
